LIQUID BURNING FUEL

George A. Rieke, Chicago, Ill.

No Drawing. Application June 27, 1950,
Serial No. 170,690

6 Claims. (Cl. 44—80)

1

This invention relates to a liquid burning fuel and particularly to an improved fuel for internal combustion engines.

A fuel embodying features of this invention is characterized by its ability to revitalize old and sluggish engines and to provide greater power output per unit quantity of fuel consumed responsive to more efficient burning coupled with the formation of a minimum amount of sludge. The apparent effect of burning fuel embodying features of this invention corresponds to that obtained by the incorporation of anti-knock agents in a fuel composition for the purpose of increasing its octane value. The undesirable effects resulting from the use of unstable alkyl metal compounds, such as tetraethyl lead, to increase the octane value are avoided because the ingredients added to the fuel composition in accordance with this invention is relatively stable under all conditions to which the fuel might be exposed.

Another important feature in this invention resides in the improved lubricating characteristics which exist on the surfaces exposed to or associated with the combustion chamber. More important, the fuel appears to have excellent anti-sludge characteristics and it has the ability to remove sludge, carbon or other decomposition products which influence the sluggishness of the motor.

In accordance with this invention a new and improved fuel for internal combustion engines is compounded by the addition to gasoline or like fuel of a small amount of a partially hydrogenated aryl compound in liquid phase. Greatest benefit is derived from the use of partially hydrogenated phenyls and particularly, the partially hydrogenated isomeric biphenyls, terphenyls, quaterphenyls, and other polyphenyls. Generally a compound such as a terphenyl is in a solid state when unhydrogenated or when completely hydrogenated yet it exists in a liquid state when partially hydrogenated in accordance with its use in this invention.

Suitable compounds for the practise of this invention may be selected of the aryl compounds or polyphenyls which have been hydrogenated to an extent ranging from thirty to sixty percent of complete hydrogenation, that is when the carbon atoms existing in the molecule are provided with thirty to sixty percent of the hydrogen could be added completely to satisfy the compound. It will be apparent that in the preparation of polyphenyls and also in the hydrogenation step, various isomeric phenyls and mixtures of phenyls

2

will be formed, such for example as in the manufacture of partially hydrogenated terphenyls, some partially hydrogenated isomers thereof will be formed as well as partially hydrogenated phenyls, biphenyls, and quaterphenyls and the like.

The desired lubricating, anti-knock and anti-sludge characteristics are secured when the partially hydrogenated aryl compound is present in the fuel in the ratio of 0.05% to 2.0% by weight 10 of the fuel composition or more specifically, when present in the ratio of one part hydrogenated terphenyl per 264 to 2144 parts by volume gasoline. Beneficial results are secured when more or less of the partially hydrogenated compound 15 is employed with gasoline or other corresponding liquid-burning fuels but it is best to make use of the least amount possible from the standpoint of cost and lubricating effects because no appreciable difference is apparent in the ability 20 of the fuel to lubricate, to solubilize carbon or sludge and to burn at a relatively steady rate.

A partially hydrogenated compound with which excellent results are secured when incorporated in gasoline is composed mostly of the 25 terphenyls but includes some biphenyls and other polyphenyls. The material hydrogenated to about 40% of its capacity is clear and mobile and has a high boiling point. It has a specific gravity of $1.004 \pm .003$ at $20^\circ C$. The material 30 exhibits a tendency to super-cool with some crystallization if maintained for a long period at temperatures below $-5^\circ C$. The vapor pressure is approximately 2 mm. of hg. at $150^\circ C$. and 230 mm. hg. at $300^\circ C$. The vaporization 35 point is about $114^\circ C \pm 6$. The material is capable of dissolving waxes and resins and is fully compatible with little if any crystallization with gasolines under normal conditions of use.

By way of illustration, but not by way of limitation, the following are examples of fuels embodying features of this invention:

Example I

31.2 pounds (3.7 gallons) of 40% hydrogenated 45 terphenyl is added to 1000 gallons of gasoline at ambient temperature and pressure. A minimal amount of agitation is desirable in the absence of agitation which would normally result from handling or transporting the resultant solvent prior to its subsequent use as a fuel for an internal combustion engine.

It is understood that the foregoing example represents only one proportionate mixture of gasoline and hydrogenated terphenyl which produces a fuel with the advantageous qualities pre-

viously particularized, namely one part hydrogenated terphenyl to approximately 264 parts of gasoline by volume, and that the proportion of the named compounds may be varied therefrom up to a proportion of one part of terphenyl to 2144 parts of gasoline by volume as previously prescribed. All mixtures within the specified limits of proportions may be compounded according to the procedure outlined in the foregoing example.

Example II

Biphenyl hydrogenated to 50% of its capacity and containing small amounts of similarly hydrogenated biphenyl, terphenyl and phenyl is 15 added to gasoline in amounts ranging from 0.05 to 2.0% by weight.

Example III

Isomeric quaterphenyls hydrogenated to 35% of its capacity and including similarly hydrogenated homologues such as biphenyl and terphenyl is compounded with gasoline in amounts ranging from 0.1 to 1% by weight of the gasoline to provide a new and improved liquid-burning fuel for internal-combustion engines.

This application is a continuation-in-part of my copending application, Serial No. 50,871, filed on September 23, 1948, now abandoned, and entitled "Anti-Knock Compound."

It will be understood that other similarly partially hydrogenated phenyls and isomeric polyphenyl compounds may be incorporated in the desired ratio with gasoline or other fuels to improve the burning characteristics and the operating characteristics of the fuel in an internal-combustion engine, such modifications being capable

4
of being made without departing from the spirit of the invention, especially as defined in the following claims.

I claim:

1. A fuel consisting essentially of 1 part hydrogenated terphenyl and 264 to 2144 parts by volume gasoline.

2. An internal combustion fuel consisting essentially of 1 part of about a 40% hydrogenated terphenyl and from 264 to 2144 parts by volume gasoline.

3. A liquid burning gasoline containing 0.05 to 2.0% by weight of a partially hydrogenated terphenyl.

4. A liquid burning gasoline containing 0.05 to 2.0% by weight of a partially hydrogenated aryl compound selected from the group consisting of biphenyls, terphenyls, quaterphenyls and polyphenyls, and mixtures thereof.

5. A gasoline containing 0.05 to 2.0% by weight of a 30% to 60% Hydrogenated phenyl compound.

6. A gasoline containing 0.05 to 2.0% by weight of a 30% to 60% aryl compound selected from the group consisting of partially hydrogenated biphenyls, partially hydrogenated terphenyls, partially hydrogenated quaterphenyls and partially hydrogenated polyphenyls, and mixtures thereof.

GEORGE A. RIEKE.
